United States Patent Office.

ISRAEL AMIES, OF PHILADELPHIA, PENNSYLVANIA.

Letters Patent No. 91,063, dated June 8, 1869.

IMPROVED HATCHWAY FOR BUILDINGS.

The Schedule referred to in these Letters Patent and making part of the same

To all whom it may concern:-

Be it known that I, ISRAEL AMIES, of the city of Philadelphia, in the State of Pennsylvania, have invented a new and useful Improvement in Hatchways for Buildings; and I do hereby declare that the following is a full, clear, and exact description of the construction and operation of the same, reference being had to the accompanying drawings, making a part of this specification, in which—

Figure 1 is a vertical section of a hatchway having my said improvement applied thereto;

Figure 2, a plan view of one of the hatches of the same; and

Figure 3, a transverse section of fig. 2 on the dotted line *x y* thereof.

Like letters and numbers of reference indicate the same parts when in the different figures.

The object of my improvement is to allow the fall or burden-rope to traverse the closed hatches above those through which the burden is to be passed without injurious friction upon, and consequent rapid destruction of the said rope, as the same is being wound and unwound around the usual operating-cylinder near the roof of the building; and also to prevent the air-draught consequent upon the necessity heretofore arising of opening the upper hatches, or of having a large slot in them, to allow the necessary traversing-motions of the said burden-rope.

My invention consists in the application to a hatch of a traversing slide, in combination with adjustable friction-rollers, operating substantially as hereinafter described.

Referring to the drawings—

A B is the hatchway;

C, the burden-rope;

D, the operating-cylinder;

E E, the hatches;

F F, the traversing slide; and

f f', the friction-rollers.

The hatches E each consists of a platform made to fit the hatchway, and hinged to the same, and also balanced by a weight, G, attached to a cord, h, which passes over a grooved pulley, a', and connects with the opposite edge of the hatch, and thus renders it more easy to raise the hatch, and also keeps it from falling shut when opened. (See fig. 3.)

Directly in line with the burden-rope C, and parallel with the side of the cylinder D, from which it is suspended, a slot, e', is made in the hatch E; and parallel with this slot two recessed guide-ways e" e" are fixed to the hatch, and between these two guide-ways e' the slide F is made to slip freely, it being also

made long enough to prevent the slot e' from being uncovered by its movements longitudinally from end to end of the hatch.

Hinged to the upper side of the slide F there are two blocks f" f", which meet together in the middle of the length of the said slide, and are each held down in contact therewith by a tension-spring, 3.

The grooved friction-rollers f' f' rotate on journals in the abutting ends of the blocks f" f", and together afford, by their grooves, a round hole, in which the motions of the rope C are confined, a more capacious opening, or slot 4, being also made through the slide F, at a part directly below the rollers.

In the operation of hoisting and lowering it will be seen that as the burden-rope C is being wound and unwound by the rotating-cylinder D, it will move the slide F longitudinally to the right and left alternately, by bearing against the friction-rollers f' f' accordingly, and that therefore all injury to the said rope will be avoided by the rotatory motions of the rollers, while the slots e', in the closed hatches above and below those required to pass the burden, will be kept closely covered, and therefore the objectionable currents of air through the said upper and lower hatches, in cold weather, will be effectually prevented; that, as the roller-blocks f" f" are hinged to the slide F, as described, they will readily yield upward, so as to let the usual hook e' on the lower end of the rope C pass without any difficulty, if the said rope should be thoughtlessly or mischievously wound up by any one without opening the hatches, and that they will also allow of the hook being entered between the rollers f' f' from above with facility.

It will also be seen that when these improved hatches are closed, all draughts of air from one story to another through the hatchway will be prevented, which is a matter of great importance in case of fire.

Having thus fully described my improvement,

What I claim as new therein, of my invention, and desire to secure by Letters Patent, is confined to the following, viz:

I claim, in combination with the hatch E, provided with the slot e' and guide-ways e" e", as described, the traversing slide F, provided with the hinged blocks f" f" and the grooved friction-rollers f' f', as described, the said parts being arranged to operate together in the manner and for the purpose described.

ISRAEL AMIES.
